DESIGN FOR BOOK ENDS

Andrew Fraser Gibson, Berkeley, Calif.

Application February 29, 1932. Serial No. 43,041

Term of patent 14 years

To all whom it may concern:

Be it known that I, ANDREW FRASER GIBSON, a subject of the King of Great Britain, and resident of Berkeley, county of Alameda, State of California, have invented a new, original, and ornamental Design for Book Ends, of which the following is a specification, reference being had to the accompanying drawing, forming part thereof.

Referring to the drawing:

Figure 1 is a perspective view of the book ends, showing the design of my invention, in this figure

the books are indicated in dot and dash lines;

Figure 2 is a side elevation of the book ends, showing my design, in this figure the books are indicated in dot and dash lines; and

Figure 3 is an end elevation of the book ends, showing my design.

I claim:

The ornamental design for book ends as shown in the accompanying drawing.

ANDREW FRASER GIBSON.
